UNITED STATES PATENT OFFICE

154,121

DESIGN FOR A COMBINED WATCH AND
BRACELET

Abbot A. Harman, New York, N. Y.

Application January 11, 1949, Serial No. 169

Term of patent 7 years

(Cl. D45—4)

To all whom it may concern:

Be it known that I, Abbot A. Harman, a citizen of the United States of America, residing at New York, in the county of New York and State of New York, have invented a new, original, and ornamental Design for a Combined Watch and Bracelet, of which the following is a specification, reference being had to the accompanying drawing, forming a part thereof.

Figure 1 is a perspective view of a combined watch and bracelet disclosing my new design.

Figure 2 is an edge elevational view thereof in a closed position.

Figure 3 is a fragmentary perspective view between the line 3—3 of Figure 1 illustrating the watch element in an open position.

I claim:

The ornamental design for a combined watch and bracelet, as shown.

ABBOT A. HARMAN.
